CLAIM

The ornamental design for a spinal fusion cage, as shown and described.

DESCRIPTION

FIG. 1 is a front, left, and top isometric view of a spinal fusion cage in an unlocked configuration.

FIG. 2 is a rear, right, and top isometric view of the spinal fusion cage in the unlocked configuration.

FIG. 3 is a front elevation view of the spinal fusion cage in the unlocked configuration.

FIG. 4 is a rear elevation view of the spinal fusion cage in the unlocked configuration.

FIG. 5 is a left elevation view of the spinal fusion cage in the unlocked configuration.

FIG. 6 is a right elevation view of the spinal fusion cage in the unlocked configuration.

FIG. 7 is a top plan view of the spinal fusion cage in the unlocked configuration.

FIG. 8 is a bottom plan view of the spinal fusion cage in the unlocked configuration.

FIG. 9 is a front, left, and top isometric view of a spinal fusion cage in a locked configuration.

FIG. 10 is a rear, right, and top isometric view of the spinal fusion cage in the locked configuration.

FIG. 11 is a front elevation view of the spinal fusion cage in the locked configuration.

FIG. 12 is a rear elevation view of the spinal fusion cage in the locked configuration.

FIG. 13 is a side elevation view of the spinal fusion cage in the locked configuration.

FIG. 13 is a left elevation view of the spinal fusion cage in the locked configuration.

FIG. 14 is a right elevation view of the spinal fusion cage in the locked configuration.

FIG. 15 is a top plan view of the spinal fusion cage in the locked configuration; and,

FIG. 16 is a bottom plan view of the spinal fusion cage in the locked configuration.

The broken lines represent portions of the spinal fusion cage and form no part of the claimed design.
